TOWER INDICATOR

Filed July 7, 1919

FIG. 1.

FIG. 4.

FIG. 2.

FIG. 3.

INVENTOR.
Richard C. Leake,
BY Neil H. Preston
ATTORNEY

UNITED STATES PATENT OFFICE.

RICHARD C. LEAKE, OF ROCHESTER, NEW YORK, ASSIGNOR TO GENERAL RAILWAY SIGNAL COMPANY, OF ROCHESTER, NEW YORK, A CORPORATION OF NEW YORK.

TOWER INDICATOR.

Application filed July 7, 1919. Serial No. 309,208.

To all whom it may concern:

Be it known that I, RICHARD C. LEAKE, a citizen of the United States, and resident of the city of Rochester, in the county of 5 Monroe and State of New York, have invented a new and useful Tower Indicator, of which the following is a specification.

This invention relates to indicating relays, which are commonly termed tower indicators or annunciators according to their use, 10 and which are used in railway signaling to indicate the position or condition of a distant device, such as a signal, track relay, or the like.

One object of this invention is to improve 15 the construction of such indicating relays by employing a few simple parts which can be cheaply manufactured and assembled, by making provision for adjustment to compensate for the slight inaccuracies in the 20 size, shape and alignment of parts occurring in ordinary commercial manufacture, and by constructing and arranging the parts of the operating mechanism so that it may 25 be readily converted to provide for any one of the various indications commonly employed in such devices.

Other objects and advantages will appear 30 as the description of the invention progresses, and the novel features thereof will be particularly pointed out in the appended claims.

In describing the invention in detail, reference will be made to the accompanying 35 drawings, in which like reference characters designate corresponding parts in the several views, and in which:

Figure 1 is a vertical section taken substantially through the center of an indicator embodying my invention, some of the 40 parts being shown in elevation for the sake of clearness;

Fig. 2 is a horizontal section taken substantially on the line 2—2 in Fig. 1 viewed 45 in the direction indicated by the arrows *a*;

Fig. 3 is a vertical section taken substantially on the line 2—3 in Fig. 1 viewed in the direction indicated by the arrows *b*; and

Fig. 4 is a fragmentary view of the front 50 of the indicator and shows a preferred form of indicator blade.

In the illustrated embodiment of the invention, I have shown it applied to a relay 55 of usual and well known construction. This

relay comprises the usual pair of coils 1—1, with a back strap 2, and pole pieces 3 fastened to a coil support 4, all of these parts being supported by the top plate 5 of the usual relay casing. The armature 6 of the 60 relay is pivotally supported at one edge to downwardly extending lugs 7 integral with coil support 4, suitable contact fingers 8 being fastened to the armature 6 and adapted to cooperate with the usual fixed contact 65 posts.

The indicator embodying my invention is housed in a suitable casing *G* (see Fig. 1), which is provided with detachable side plates 9 and is secured to the back strap 70 2 of the relay in any convenient manner, as by screws 10 threaded into tapped holes in said back strap 2. The front end of the indicator casing is formed with a flanged plate 11, preferably circular in shape, which 75 constitutes the background for the indicator blade 12, said plate 11 being provided with the usual glass roundel 13 held in place by a bezel ring 14 fastened to the casing by screws. The indicator blade 12, illustrated 80 as a miniature semaphore, is riveted to one end of a horizontal shaft 15 which is journaled in bushings supported by the casing *G*, as shown in Figs. 1 and 2. Suitable stop pins 12^a in the plate 11 limit the movement 85 of the indicator 12. This shaft 15 is provided with two parallel discs 16, preferably formed integral with said shaft, having a plurality of sets of aligned holes, designated A, B, C, and D, drilled therein eccentrically 90 with the axis of said shaft (see Fig. 3), for a purpose hereinafter explained. A link 17 is loosely connected at one end between said discs by means of a pin 18 passing through one set of said holes, and at its other end 95 by means of a pin 19 to the bifurcated jaw 20 of a counter-balanced rocking lever 21. The jaw 20 is wide (see Fig. 3), and a spacing sleeve 22 is mounted on the pin 19 between said link 17 and one side of the 100 jaw 20. This rocking lever 21 is pivotally supported near its other end in lugs 23 formed integral with the base of the indicator casing *G*.

The rocking lever 21 is operated by an 105 up-and-down rod 24, the upper end of which fits loosely in a recess in one end of an adjusting screw 25 threaded into a tapped hole in said rocking lever, said screw being provided with a clamping or lock nut 26. 110

The rod 24 extends downward inside of a protecting tube 27 and through the adjustable residual screw 28, and rests at the lower end on the armature 6. The up-and-down rod 24 is guided at its upper end by the adjusting screw 25 in the rocking lever 21, and at its lower end by the residual screw 28. The residual screw 28 is provided with a slot, so that when the indicating mechanism is removed, this screw may be adjusted to vary the air gap of the armature 6 by a screw driver or similar tool of appropriate shape.

With the relay de-energized, the parts of the indicator assume the positions shown in Figure 1, and the indicator blade 12 is in the zero degree or danger position. When the relay is energized, and its armature 6 is attracted, the up-and-down rod 24 is forced upward by said armature and raises the lever 21. With the link 17 connected to the discs 16 on the shaft 15 as shown in Fig. 3, this movement of the lever 21 causes the indicator 12 to move in a counter-clockwise direction to its 90 degree or clear position, as shown in dotted lines in Fig. 4. When the relay is again de-energized, its armature 6 returns by its own weight to its lower position, shown in Fig. 1; and the lever 21, being biased to the lower position, returns the indicator 12 to its horizontal or danger position. The up-and-down rod 24 merely rests upon the upper face of the armature 6, so that said armature is free to drop as soon as the energizing current is cut off, and can not be held in its upper position by the binding or sticking of any operating parts of the indicator. By adjusting the screw 25, compensation may be made for slight inaccuracies occurring in ordinary manufacture, such as variations in the movement of the armature 6, which is adjusted by the residual screw 28 for the most efficient performance and which will vary somewhat in the various relays.

The aspects or indications of the indicating relay used in practice are often different, according to the particular application of the relay and the preference of the user. Sometimes an indicator moving from the zero degree or horizontal position to the 90 degree or vertical position in the upper righthand quadrant is desired, and sometimes a 45 degree movement, or a 60 degree movement, in this upper righthand quadrant or some one of the other quadrants. One important feature of my invention is the provision which is made to permit the various parts of my indicating relay to be readily adjusted or assembled, without adding or substituting different parts, so as to give any one of the various indications in the several quadrants commonly required. In the arrangement shown in the drawing, the indicator 12 moves from the zero to the

90 degree position in the upper righthand quadrant. To obtain a movement of the indicator 12 from the zero to 45 degree position in the same quadrant, the connection in the upper end of the link 17 is changed from the holes A in the discs 16 to the holes B (see Fig. 3). The holes B in the discs 16 are at a greater radial distance from the axis of the shaft 15, so that for the same movement of the rocking lever 21 and the resultant vertical movement of the link 17, a smaller angular movement of the shaft 15 will be obtained. The holes B may be located so as to obtain a 45 degree movement of the indicator without changing the movement of the rocking lever 21, but I find it expedient and preferable to locate the holes B so as to obtain a movement of the shaft 15 averaging between 45 and 60 degrees; and with this particular location of the sets of holes B, the adjusting screw 25 must also be backed off to shorten the throw of the link 17, as well as shifting the connection of said link to the sets of holes B, in order to obtain a 45 degree movement of the indicator. A 60 degree movement of the indicator in the upper righthand quadrant is obtained by adjusting the screw 25 with the upper end of the link 17 connected to the set of holes B. Similar 90 degree, 45 degree, or 60 degree movements of the indicator may be obtained in the lower lefthand quadrant by connecting the link 17 to the set of holes A or B, as the case may be, and by adjusting the nut 25 accordingly, the indicator 12 and the stop pins 12^a being of course changed to correspond. For indications in the upper lefthand quadrant and the lower righthand quadrant, the upper end of the link 17 is connected with the sets of holes C or D, as the case may be, and the lower end of this link is shifted over the other side of the spacing sleeve 22 (see Fig. 3), adjustments being made corresponding to those just described in connection with the upper righthand and the lower lefthand quadrants. This universal feature of my indicating relay is an important characteristic of my invention, since it facilitates the manufacture of an indicating relay to meet different specifications and requirements, and also makes it possible to readily change over an indicating relay already in service so as to get any other indication or aspect desired. It will be observed that different indications in the same quadrant may be obtained with a relay in service by adjustment only, while it may be necessary to position the indicator on the shaft properly for change-over into another quadrant.

Another important feature of my invention is the fact that the mechanism of the indicator may be applied to an ordinary relay, without requiring change in the con-

struction of the relay, or modifying its reliable and effective operation. Thus, in commercial manufacturing, a standard relay, suitable for a track relay or line relay 5 may be constructed, and this relay in turn converted into a tower indicator or annunciator by attaching to it the few and simple parts, constituting the indicator and its operating mechanism.

10 Although I have particularly described the construction of one physical embodiment of my invention, and explained the operation and principle thereof, nevertheless, I desire to have it understood that the form 15 selected is merely illustrative, but does not exhaust the possible physical embodiments of the idea of means underlying my invention.

What I claim as new and desire to secure 20 by Letters Patent of the United States, is:—

1. In an indicating relay having a movable armature, an up-and-down rod resting upon said armature and raised by the attraction thereof, a biased rocking lever 25 actuated by said rod, and indicating means movable from one indicating position to another in a vertical plane and operatively connected to said rocking lever, said rod being guided by said rocking lever.

30 2. In an indicating relay having a movable armature, an up-and-down rod resting at its lower end upon said armature, a biased rocking lever having a pocket in which said rod is adapted to rest, a shaft, 35 an indicator attached to said shaft, and means connecting said rocking lever and said shaft.

3. In an indicating relay having a movable armature, an up-and-down rod resting at its lower end upon said armature, a biased rocking lever including a main portion and an adjustable operative connection 40 engaging the upper end of said rod, an indicator shaft, and a link for operatively connecting the rocking lever and said shaft, whereby the indicator shaft may be rocked in response to movement of said armature and its relation to said armature may be varied by changing the relation of the adjustable portion of said rocking lever 45 engaging the upper end of said rod to that of the main portion of said rocking lever.

4. In an indicating relay having a movable armature, a shaft, an indicator attached to said shaft, a biased rocking lever 50 operatively connected to the armature of the relay, a link pivotally connected at one end to said rocking lever, and means on the shaft adapted to permit connection of the other end of said link at different points eccentric with the axis of the shaft and on opposite sides thereof, whereby the parts 55 may be adjusted to cause the shaft and indi-

cator to move through different angles and in either direction when the armature is attracted.

5. In an indicating relay having a movable armature, an up-and-down rod resting at its lower end upon an armature of the relay, a biased rocking lever having adjustable means cooperating with the upper end of said rod, a link pivotally connected at one end to said rocking lever, and means on the shaft permitting pivotal connection of the other end of said link at different radial distances from the axis of the shaft and on opposite sides thereof.

6. In an indicating relay having a movable armature, a biased rocking lever operatively connected to the armature of the relay, an indicator shaft, a member secured to said shaft and having a plurality of holes therein located at different distances from the axis of the shaft and on opposite sides thereof, and a link pivotally connected 80 at one end to the rocking lever and at its other end to said member in one of the holes therein.

7. In an indicating relay having a movable armature, an up-and-down rod resting upon the armature, a biased rocking lever having an adjusting screw therein, said screw having a recess in its end receiving the upper end of said rod, an indicator shaft, parallel discs integral with said shaft and having a plurality of sets of aligned holes therein located at different distances from the axis of the shaft and on opposite sides thereof, and a link pivotally connected 90 at one end to the rocking lever and at its other end to said member in one of the holes therein.

8. An indicating relay comprising a pair of coils and a movable armature, an up-and-down rod disposed vertically between said coils and resting upon the armature, an indicator casing supported above said coils, a movable indicator in the casing and visible from the outside thereof, and biased operating means supported by and inclosed in the casing operatively connected to the indicator and engaging the upper end of said rod for causing movement of the indicator when said rod is raised and lowered 100 by the movement of the armature to the attracted and retracted position respectively.

9. An indicating relay comprising an indicator movable in a vertical plane, a horizontal shaft for moving the indicator, an armature, a vertically movable rod resting on the armature, and biased means operatively connected to said shaft and bearing against the upper end of said rod for rocking the shaft as the rod is raised and re-

turning the shaft as the rod is lowered, said means including two separate adjustable connections of which one serves to take up lost motion and the other facilitates varying 5 the extent of movement of said shaft with respect to said rod.

10. An indicator attachment for relays comprising a casing having a glass covered background, a horizontal shaft supported in 10 the casing, an indicator movable with said shaft, a movable member in the casing, and adjustable means connecting said member and shaft and permitting the shaft and indicator to move through different angles 15 and in either direction for the same movement of said member.

11. An indicating relay comprising a movable armature, an indicator movable in a vertical plane, and biased means for operatively connecting the armature and indicator, said means being adjustable to change 20 the extent and direction of movement of the indicator.

12. An indicating relay comprising a 25 movable armature, a hollow adjustable residual pin for said armature, an indicator, and means including a rod guided in said residual pin for operatively connecting the indicator and said armature.

30. 13. An indicating relay comprising an armature supported for up-and-down movement, a horizontal shaft, an indicator movable with the shaft, a vertically movable operating member adapted to rest on said 35 armature, and means operatively connecting said shaft and member, said means being adjustable to cause the shaft to move 40 through different angles and in different directions for the same movement of the operating member.

14. An indicating relay comprising a lower casing containing an armature and contact fingers, an upper casing containing an indicator and biased operating means 45 therefor, an up-and-down rod operatively connecting the armature and said operating

means, and a tube connecting said two casings and surrounding said rod.

15. In an indicating attachment for relays of the conventional tractive type used in 50 railway signaling, the combination with the casing of the relay, the pair of cores and the coils thereon extending above said casing, the tilting armature within the casing attracted by the lower ends of said cores, 55 of an enclosed indicator casing supported wholly by the upper ends of the cores and provided with a background and a cover glass, a horizontal shaft supported within the indicator casing and projecting through 60 the background, an indicator fastened to the projecting end of said shaft, a rocking lever pivotally mounted on a horizontal axis within the indicator casing and biased to one extreme position, means operatively 65 connecting said lever and said shaft to cause rotation of the shaft as the lever is tilted, an up-and-down rod extending vertically from the indicator casing to the relay casing and resting at its lower end upon 70 the relay armature, the upper end of said rod engaging the rocking lever and acting to shift it from its biased position when the relay armature is attracted.

16. In an indicating attachment for 75 relays of the type described, the combination with the tilting armature of the relay, of an up-and-down rod resting at its lower end on said armature near its free edge, a horizontally disposed shaft supported above the armature, an indicator fastened to said shaft, a biased rocking lever arranged to be tilted from its biased position by the upward movement of said rod, and means operatively connecting said lever 80 and shaft to cause turning of the shaft as said lever is tilted, said means being adjustable to vary the extent or direction of movement of the shaft for the same movement of the lever.

RICHARD C. LEAKE.
